UNITED STATES PATENT OFFICE

JOHN R. HOFFMAN, OF MADISON, WISCONSIN, ASSIGNOR TO MADISON-KIPP CORPORATION, OF MADISON, WISCONSIN, A CORPORATION OF WISCONSIN

FLUID OPERATED TOOL

Application filed January 31, 1931. Serial No. 512,700.

This invention relates to fluid-operated tools and particularly to those of the impact or percussive type.

Primarily, it is the object of my invention to provide for shop or general use a small, but practical, high speed tool of the character mentioned. It is proposed to make the tool of the lightest metal possible, consistent with efficiency, and to so design and shape the tool as to adapt it for one-hand manipulation by the operator.

An important feature of the tool is the efficient utilization of the exhaust motive fluid from the impact motor for operating the valve means for distributing the motive fluid to the hammer cylinder. Rapid distribution of the motive fluid to the hammer cylinder and positive action of the distributor valve are also important features of the device.

A further feature contributing to the reliability and efficiency of operation of the tool is the special arrangement for distribution of the motive fluid, whereby greater force is applied to the hammer on its working stroke than on its return. Improved means for supplying lubricant to the moving parts of the tool also are provided.

A practical embodiment of the device is shown in the accompanying drawings, in which:

Fig. 1 is a side elevation of the tool with certain parts broken away to show the turbine runner which operates the distributor valve;

Fig. 2, a front elevation of the same;

Fig. 3, a longitudinal section taken on line 3-3 of Fig. 4, showing the distributor valve in position to feed motive fluid to the right end of the hammer cylinder;

Fig. 4, a transverse section on the line 4-4 of Fig. 3, with the distributor valve in the same position;

Fig. 5, a section taken on line 5-5 of Fig. 3, showing the manner in which the exhaust fluid from the hammer cylinder operates the turbine runner;

Fig. 6, a section on line 6-6 of Fig. 3, further disclosing the same feature;

Fig. 7, a section taken on line 7-7 of Fig.

3, with the distributor valve in the position of Figs. 3 and 4;

Fig. 8, a section taken on line 8-8 of Fig. 4, showing the segmental groove in the distributor valve in position to feed motive fluid to the right end of the hammer cylinder;

Fig. 9, a similar view showing the segmental groove in position to feed the fluid to the left end of the cylinder;

Fig. 10, a perspective of the turbine runner and the distributor valve or shaft;

Fig. 11, a longitudinal section of the bearing for the distributor valve, as it appears in Fig. 4;

Fig. 12, a section on line 12-12 of Fig. 11;

Fig. 13, a section on line 13-13 of Fig. 1, showing the details of the chisel or steel-holding means; and

Fig. 14, a perspective of the same removed from the tool.

As shown in the drawings, the body 1 of the tool is made up of a barrel 2 and a stock or grip 3. In order that the tool may be comfortably grasped in one hand and manipulated with a minimum of effort on the part of the operator, these parts are designed to closely simulate the corresponding parts of a standard type pistol or revolver. This, taken with the fact that the body of the tool preferably is a die-casting of extremely light metal, such as zinc, enables the operator to readily manipulate the tool under practically any working conditions.

The barrel portion of the tool, as best shown in Fig. 3, is formed with a continuous passage therethrough. At its rear end this passage forms a piston or hammer chamber 4, the rear end of which is closed by a pair of slotted screw plugs 5, 6. The forward end of the passage forms a barrel chamber 7 into which slidably fits the shank 8 of a chisel or other steel 9. In cross section, barrel chamber 7 and steel shank 8 are shaped similarly preferably in the form of a pentagon. This serves to prevent rotation of the tool in its socket and thereby maintains its cutting edge always in a definite relation to the rest of the tool.

Intermediate hammer cylinder 4 and barrel 100

chamber 7 is a reduced passage 10 in which an anvil or plunger 11 is located for reciprocatory movement. Anvil 11 has an enlarged head 12 which normally, that is, when the 5 tool steel 9 is not pressing against the work, engages the left end of hammer cylinder 4, as shown in Fig. 3. The length of plunger 11 is such that, when the plunger is in this position, its outer end projects a short distance 13 into barrel chamber 7 and abuts the 10 inner end of steel 9.

Located in chamber 4 is a hammer 14 adapted to control exhaust ports 15, 16 leading from the chamber. Inlet ports 17, 18 are provided near the ends of chamber 4, and distribution of motive fluid to these ports is controlled by certain valve mechanism to be described shortly.

When the operator grasps the tool in his 20 hand and forces steel 9 against the work, the steel pushes anvil 11 inwardly until it assumes the dotted line position of Fig. 3. At this time, head 12 of the anvil is spaced 25 from the end wall of chamber 4 and steel 9 abuts the inner end of its socket 7. Motive fluid being admitted to the right end of hammer chamber 4 through inlet 18, hammer 14 is forced to the left and delivers a blow to the head of anvil 11. This is transmitted to 30 chisel 9 which is thereby driven into the work against the pressure exerted by the operator on the tool. The normal stroke of the tool steel is indicated by the distance 13, Fig. 3.

Improved means are provided for preventing steel 9 from dropping out of the tool, 35 but which at the same time permit reciprocation of the steel in its socket in accordance with the desired stroke. This retaining means is shown in Figs. 1, 3, 13 and 14. It 40 comprises a semicircular spring member 19 perforated at each of its ends to receive the head 20 of a removable plug or pin 21. Spring member 19 is snapped into place about the lower side of the barrel of the tool, as 45 shown in Figs. 3 and 13, and serves to maintain the tool-steel-holding plugs 21, 21 in place in suitable openings provided in the sides of the barrel. The inner ends of plugs 21, 21 are rounded and project sufficiently into 50 barrel chamber 7 to engage an annular groove 22 formed in the shank 8 of the steel. Each plug 21 is formed with an annular flange 23 for properly positioning it in the opening in the barrel. This flange also provides for 55 proper interengagement between the retaining spring 19 and the plug so as to hold the latter in place. The diameter of the inner end of plug 21 and the length of the annular slot 22 in the steel are such as to preclude interference with the normal stroke or reciprocatory movement of the steel. A continuous rib 19' is formed on the barrel of the tool surrounding spring member 19. This serves to position the spring member and 60 prevent its accidental removal.

The means for distributing the motive fluid to hammer chamber 4 and the exhausting of the motive fluid from this chamber will now be described. Mounted for rotation in the body of the tool transversely of hammer chamber 4 and substantially midway between its ends is a distributor valve or shaft 24. This member is best shown in Figs. 3 and 4. Shaft 24 is located within a cylindrical bearing 25 fixed in a suitable opening 26 formed 75 in the body of the tool.

As shown in Fig. 4, the left side of the tool body is provided with an annular extension 27 which forms a turbine runner chamber 28. The left end of valve shaft 24 80 extends into chamber 28 and has a runner 29 fixed thereon.

Runner 29, as shown in detail in Fig. 10, 85 is provided on its inner face with buckets 30 against which the exhaust fluid from hammer chamber 4 is adapted to impinge, as explained later, in order to rotate the runner and the shaft or valve 24 to which it is attached. The parts are arranged so as to cause runner 29 to rotate in a counterclockwise direction, as viewed in Figs. 1 and 3. An annular flange 31 at the inner ends of runner buckets 30 prevents escape of the fluid at this point. As a result, the fluid flows from the periphery of the runner and passes out 90 of the exhaust port 32 provided in the side of runner chamber 28, see Figs. 1 and 2.

The outer side of runner chamber 28 is 95 closed by a cover plate 33, which preferably is threaded into body extension 27. Spanner wrench depressions 34, 35 are provided for removing or replacing cover 33. Centrally of the inner side of the cover plate, a socket 36 is formed to receive a ball bearing 37. When the cover plate is in place, bearing 37 engages the inner end of shaft 24 100 and functions as a thrust bearing therefor.

Referring particularly to Fig. 10, it is to be noted that shaft or valve 24 is formed near runner 30 with an annular groove 38. Also formed on the periphery of shaft 24, but spaced longitudinally from annular groove 38, is a segmental groove 39 which is connected to groove 38 by a longitudinal groove 105 40.

Segmental groove 39, as shown in Figs. 8 and 9, is adapted, upon rotation of valve 24, to be alternately connected to a pair of diametrically opposed openings 41, 42 in the sides of valve bearing 25. In this manner, 110 motive fluid is distributed either by way of inlet passage 43 to inlet port 17 at the left end of hammer chamber 4, or by way of inlet passage 44 to inlet port 18 opening into the right end of the hammer chamber. Attention is directed to the fact that, as shown 115 in Figs. 8 and 9, inlet passage 43 and opening 41 in bearing 25 leading to the left end of hammer chamber 4 are of smaller diameter than bearing opening 42 and passage 44 120 125

leading to the right end of the chamber. This is for the purpose of restricting the flow of motive fluid into the left end of chamber 4, but permits full pressure to act on hammer 14 at the right end of chamber 4. In this manner, the full force of the motive fluid is applied to the hammer on its working stroke, and a correspondingly heavy blow delivered thereby to the chisel 9. Only sufficient fluid 10 is fed to the left end of the hammer chamber to return the hammer to the right preparatory to its next working stroke.

The motive fluid from the source of supply is delivered to distributor valve 24 by 15 means of an upright passage 45 in the handle of the tool, which connects at its upper end to an opening 46 in the under side of valve bearing 25. The motive fluid delivered to this point passes into annular groove 20 38 in shaft 24 (Fig. 3), and thence to segmental groove 39 by way of groove 40 (Fig. 4), the fluid being distributed by the segmental groove to the opposite ends of hammer chamber 4, as explained above. 25 The motive fluid is furnished to the tool by way of a passage 47 in the handle 3 to the lower end of which a hose 48 leading from a source of pressure fluid supply is connected. The motive fluid flows from passage 47 into 30 a smaller passage 49, the inner end of which opens into a valve chamber 50.

As shown in Fig. 3, the outer end of the valve chamber is closed by a slotted screw plug 51. The inner end of valve chamber 50 connects by a reduced passage 52 with the lower end of upright passage 45 leading to the distributor valve or shaft 24.

Passage of motive fluid from valve chamber 50 into passage 52 is controlled by a 40 throttle valve 53, the head of which is normally held in closed position against valve seat 54 by means of a coil spring 55 interposed between the head of the valve and screw plug 51. The stem 56 of the throttle valve extends slidably through an opening 57 in the tool handle from which it projects 45 for engagement by valve-actuating trigger 58, see Figs. 1 and 3. Trigger 58 is carried by a pivot pin 59 mounted on the body of the tool. Coacting lugs 60, 61 on the barrel of the tool and the trigger, respectively, 50 serve to maintain the trigger in proper operating relation to the stem 56 of the throttle valve.

As stated hereinbefore, hammer 14 controls the exhausting of the motive fluid from chamber 4 through exhaust ports 15, 16. In order to conduct the exhaust fluid from the hammer chamber to the turbine runner 29, whereby the distributor valve 24 is actuated, 55 exhaust port 15 connects at its lower end to a horizontal passage 62 (Figs. 3 and 7). At its forward end passage 62 opens into a downwardly inclined duct 63 (Fig. 6) from which the exhaust fluid is ejected against the

buckets of runner 29 in order to rotate it as indicated by the arrow.

As shown in Fig. 3, the lower end of exhaust port 16 connects with a second horizontal passage 64, the latter in turn opening 70 into an upwardly inclined duct 65 (Fig. 5). From duct 65 the exhaust fluid also is ejected against the buckets of runner 29 at the opposite side of the runner in order to assist in operating it. The arrangement of inlet ducts 63, 65 and exhaust port 32 is designed to circulate fluid about the runner and bearing 37 to cool these parts. It will be noted that the inner ends of horizontal exhaust passages 62, 64 are located at the opening 26 in the tool 80 in which distributor valve bearing 25 is mounted. Bearing 25 serves effectively to close the ends of passages 62, 64, so that the exhaust fluid cannot leak out at these points.

No claim is made herein to the anvil 11 85 and throttle valve 53, since both of these features form part of the subject matter and are claimed in an earlier application filed by me on January 30, 1931, Serial Number 512, 446. Certain features of the motive fluid distributing means described herein are also 90 covered by said earlier application.

More efficient lubrication of the moving parts in the present device is obtained by the lubricant-supplying means located in fluid duct 47 in the handle. This comprises a tubular sheet metal spool 66 provided with flared ends 67, 68, for properly supporting it in passage 47. Surrounding the spool is a 95 layer or winding of felt or wicking 69 which is adapted to be saturated with lubricant through an opening 70 in the side of the handle, see Fig. 4. A screw plug 71 normally closes this port. The body of spool 66 is provided with a small opening 72 near 100 its upper end and a similar opening 73 adjacent its lower end. Located against the lower end of spool 66 in passage 47 is a small mesh screen 74, which serves to prevent the 105 entrance of foreign material into the tool. 110

With this arrangement, the pressure fluid entering the passage 47 is broken up into a series of fine streams by screen 74 and flows through spool 66. In its passage through the spool, the fluid, due to openings 72, 73 in the spool, serves to pick up a certain amount of lubricant from the felt and carry it in the form of a mist through the various 115 passages of the device.

Normally coil spring 55 serves to maintain throttle valve 53 closed, thereby preventing passage of the motive fluid to the operating parts of the tool. In use, operation of trigger 58 opens the throttle valve. As a 120 result, motive fluid flows from valve chamber 50 past the throttle valve and upwardly through duct 45 into annular groove 38 of the rotary distributing valve 24. From here the fluid passes to segmental groove 39 and 130

is distributed to one end or the other of hammer chamber 4 to actuate the hammer.

Movement of the hammer 14, as explained, opens either exhaust port 15 or 16, according to the position of the hammer, and the exhaust fluid is ejected alternately from ducts 63, 65 to rotate turbine runner 29 and with it the valved shaft 24. Thus, it will be seen that operation of the rotary distributor valve 10 is positively controlled, so as to properly and rapidly feed motive fluid to the hammer chamber. It has been found that use of the particular type of distributor valve set forth herein is highly conducive to successful operation of high speed tools of the character in question. Likewise, utilization of the exhaust fluid from the hammer chamber, in the manner described, to control directly the distribution of motive fluid to the hammer chamber is found to be much preferred over the various other proposed arrangements.

It is obvious that various structural changes can be made in the device illustrated and described herein without departing from the scope of the invention, and it is not intended to restrict it to the means described, except as the same may be limited by the appended claims.

What is claimed is:—

30 1. In a fluid-operated hand tool of the character described, the combination of a tool body formed with a piston chamber having inlet and exhaust ports; a piston located in said chamber and adapted to control said 35 exhaust ports; a rotary valve for controlling distribution of motive fluid to said inlet ports; a turbine runner attached to said valve, the exhaust ports leading to said runner for actuation thereof solely by the exhaust fluid; and valve controlled means for supplying motive fluid only to said distributor valve.

2. In a fluid-operated hand tool of the impact type, the combination of a tool body 45 formed with a hammer chamber having front and rear inlet ports; a reciprocating hammer in said chamber adapted to control exhaust ports leading therefrom; a rotary shaft valve for controlling distribution of motive fluid to the inlet ports, said shaft valve being disposed transversely of the chamber 50 midway between the inlet ports; a turbine runner fixed on said shaft valve in a compartment in the tool body at one side of the 55 chamber, the exhaust ports leading to said runner to actuate the latter solely by the exhaust fluid, said tool body being formed with a relatively large passage leading from said rotary valve to the rear inlet port and a relatively small passage leading from said valve 60 to the front inlet port; and valve controlled means for feeding motive fluid only to the distributor valve.

3. In a fluid pressure operated hand tool, 65 the combination of a tool body having a pis-

ton chamber provided with inlet and outlet ports; a piston in said chamber for controlling said outlet ports; pressure fluid distributor means for said cylinder; a turbine runner for operating said distributor means, said 70 exhaust ports leading to said runner for actuation of the latter by the exhaust fluid at all times during operation of the tool; and means for conducting pressure fluid to the distributor means.

4. In a pressure fluid operated hand tool of the impact type, the combination of a tool body provided with a motor chamber having inlet ports leading thereto; a piston located in said chamber and adapted to control exhaust ports leading therefrom; means for controlling distribution of motive fluid to said inlet ports, said means including a turbine runner and a ported shaft therefor arranged for operation solely by the exhaust fluid from said chamber; and valve means for supplying motive fluid only to said distributing means.

5. In a fluid-operated hand tool of the type described, the combination of a tool body formed with a piston chamber having fluid inlet means and fluid exhaust means; a piston in said chamber adapted to control said exhaust means; a rotary valve for controlling distribution of motive fluid to said fluid inlet means; a rotary, fluid motor connected to said rotary valve, the fluid exhaust means leading to said fluid motor for actuation thereof solely by the exhaust fluid; and valve-controlled means for supplying motive fluid only to said distributor valve.

6. In a fluid-operated hand tool of the impact type, the combination of a tool body having a hammer chamber provided with inlet and exhaust ports; a reciprocating hammer 105 in said chamber for controlling escape of fluid from all of said exhaust ports to the atmosphere; a rotary valve for controlling distribution of motive fluid to said inlet ports; a turbine runner attached to said rotary valve, all of said exhaust ports leading to said runner and being in free communication therewith at all times to actuate the runner by the entire exhaust from the hammer chamber; and valve-controlled means for 110 supplying motive fluid only to the distributor valve.

In testimony whereof I have signed my name to this specification.

JOHN R. HOFFMAN.
